ELECTROLYTIC PHONOGRAPH PICKUP

John J. Root, New York, N. Y.

Application January 15, 1946, Serial No. 641,328

18 Claims. (Cl. 179—100.41)

1

This invention relates to the production of electrical voltages in response to sound frequency actuation. It is particularly directed to electrical pick-up units such as may be used with conventional phonograph records or to microphones which generate electrical impulses pursuant to sound waves impinging on their diaphragms.

Referring particularly to phonograph pick-up units, a widely used device is the well known Rochelle salts crystals which vibrate mechanically when actuated by sound waves and generate a corresponding alternating voltage by piezoelectric action. Another type of pick-up unit is the so-called dynamic or magnetic unit. This type relies upon the production of a magnetic field and the cutting thereof by a movable armature so as to produce alternating voltages through electromagnetic induction.

The above-mentioned self-generating units each have disadvantages in their operation. For example, the crystal type develops rather low voltages and is fragile. The magnetic type is heavy and usually requires counter balancing by an oppositely directed force so as not to press down too heavily on the record. In both systems harmonics may be produced and damping of the voltage generating movements is often required to overcome such defects.

Bearing the foregoing in mind, it is an object of the present invention to produce a self-generating type of pick-up unit which shall produce considerably higher voltages than do conventional pick-up devices.

Another object of this invention is to produce a pick-up unit of extreme lightness so as not to bear down excessively on a phonograph record, for example.

Another object of this invention is to produce a light-weight pick-up unit which shall have high sensitivity, low noise level, high fidelity and shall be sufficiently sturdy to resist damage through ordinary handling thereof.

Another object of my invention is to produce such a device which shall be constructed so as to be suitable for both simple or push-pull inputs to an audio amplifier and which may be adapted to either low or high impedance amplifiers.

Other objects of my invention will be apparent from the following description, it being understood that the above general statements of the objects of my invention are intended to describe and not limit it in any manner.

In the drawings,

Fig. 1 is a top plan view of a pick-up unit con-

2

structed according to the present invention, the top thereof being removed to illustrate the position of its parts.

Fig. 2 is a cross-sectional view taken downwardly through the central portion of the unit.

Fig. 3 is a somewhat diagrammatic view illustrating the electrical action of the electrodes within the unit.

Fig. 4 is a cross-sectional view similar to Fig. 2 and illustrating a modified embodiment.

Fig. 5 is a diagrammatic view of the electrical action of Fig. 4, but illustrating a further development thereof.

The device as illustrated is formed of plastic material such as one of the well known synthetic resins, typical of which are cellulose acetate, polystyrene and various acrylate and vinyl resins. However, any equivalent material, such as rubber, or metal if desired, may be utilized.

The body 10 of the unit is a chamber having relatively thick walls 11 and a thin floor 12 which is preferably, but not necessarily, provided with a corrugation 13. Disposed centrally of the floor 12 and integral therewith is the needle holder 14 in which a set screw 15 retains a phonograph needle 16. The needle holder 14 by its integral formation with the thin floor 12, is flexibly connected to the body 10 so as to be capable of pivotal movement relative thereto with the axis 30 at the pivot point 17. While the needle holder 14 is rigid compared to the floor 12, it is sufficiently narrow to permit pivotal actuation thereof as hereinafter described. It will be observed that the needle holder 14 extends into the chamber formed by the body 10 of the unit.

Secured to the internally disposed end of needle holder 14 is an electrode member 18 which partakes of the pivotal movement of the holder. Thus, referring to Fig. 2, the electrode member 18 is illustrated as being tilted in a vertical plane, by virtue of lateral actuation of needle 16. Electrode member 18 is dual in nature and may be formed of two dissimilar metals designed to act as positive and negative plates or electrodes when immersed in a suitable electrolyte. Many metals exhibit this function. For example, lead peroxide and sponge lead will form positive and negative electrodes respectively when immersed in a solution of sulphuric acid and water. Similarly, nickel peroxide and finely divided iron will form the positive and negative electrodes respectively in an alkaline type of electrolyte. In the present embodiment, a simple combination of zinc and copper plates is utilized. Such combination produces a negative terminal

for the zinc plate and a positive terminal for the copper plate. While various and conventional types of electrolytes may be employed, a high resistance electrolyte such as ethylene glycol which may have added thereto an acid or alkaline substance is most effective. In any event, a slightly conductive electrolyte such as very dilute sulphuric acid or the ethylene glycol electrolyte above mentioned not only retards local action on the electrode members, but permits the high voltages to be developed and utilized as hereinafter described, the electrolyte being disposed in the body 10.

The electrode members 18 may be formed by welding very thin zinc and copper plates together to produce a laminated construction. It is also practical to electrodeposit a zinc plate on a thin copper member or reverse the procedure in that a zinc member may be copper-plated. The electrodeposited plate should be of the same thickness as the member upon which it is deposited. It will be understood that the use of zinc and copper combinations is optional and that other materials, such as graphite, silver and various other substances may be employed.

Referring to Fig. 1, the electrode member 18 is connected by insulating post 19 to another electrode member 20 constructed as electrode 18 but having its plates reversed relative thereto. In other words, the zinc plate is uppermost, whereas in the central electrode 18 the copper plate is uppermost. Central electrode 18 is likewise connected to electrode 21 by rigid insulating post 22. Electrode members 20 and 21 are supported by a side wall of body 10 by pivot members 23 and 24 which, like the posts 19 and 22, may be of plastic material and formed with pointed ends so as to decrease friction with any type of bearing means provided in said side wall. Said bearing means may take the form of an ordinary depression. It will be apparent that actuation of the needle 16 as illustrated in Fig. 2 will pivot the electrode members 18, 20 and 21 bodily within the pick-up unit.

Disposed laterally of the pivoted members are the end electrode members 25, 26 and 27 on one side thereof, and the electrode members 28, 29 and 30 on the other side thereof. The laterally disposed electrode members are stationary and have the same sequence of plate disposition as has the turnable section. Thus, the center uppermost electrode plate is copper, while the end uppermost plates are zinc. Any suitable means for supporting the stationary plates in the body 10 may be employed. Thus a channel member 31 which frictionally engages electrode members 25, 26 and 27, is formed with a post 32 which is retained against a side wall of the body 10 as by a set screw 33. Channel member 31 is of insulating material such as one of the thermoplastic materials of which the body 10 is formed. A similar method of support is provided for electrode members 28, 29 and 30, the channel member 34 having the set screw 35 engaging the post 36. A metallic wire 37 serving as one terminal of the unit is led through a side wall of body 10 where it may be embedded and is conducted through channel 31 to electrode member 25. Similarly, a metallic wire 38 is embedded in an opposite side wall and is conducted to electrode member 30 so as to form an opposite terminal. In order to maintain proper continuity between the successive electrode members, member 28 is connected by wire 39 to mem-

ber 29, while member 26 is connected by wire 40 to member 27.

Referring to Fig. 2, in the absence of actuation of the needle 16, member 18 is disposed in the same plane as members 26 and 29. The body 10 is filled with an electrolytic solution, as stated above. Accordingly, interactions between opposite electrode plates will be produced, tending to generate electrical voltages. However, any interaction between the zinc plate of member 26 and the copper plate of member 18 is neutralized or cancelled by the action of the copper plate of member 26 with the zinc plate of member 18. Accordingly, there will be no difference of potential between electrode members 26 and 18. The same condition will prevail with respect to any potential difference between member 18 and member 29. However, lateral actuation of the needle 16 in response to the waves in the grooves of a phonograph record will at any one time produce a condition such as illustrated in the dotted lines of Fig. 2. It will be noted therein that the zinc side of electrode member 18 is presented so as to have a greater co-acting surface with the copper side of member 26. Conversely, the copper side of member 18 is withdrawn with respect to co-action with the zinc side of member 26. Accordingly, a positive voltage will be developed at electrode member 26, while a negative voltage will be developed on the zinc side of central electrode member 18. Considering now the co-action between electrode member 18 and member 29, it will be observed that the tilting of member 18 presents its copper side to member 29 so as to effect a co-action with the zinc side of member 29. Simultaneously, the zinc side of member 18 is withdrawn in respect to co-action with the copper side of member 29. Accordingly, a positive voltage is developed at the copper side of member 18, while a negative voltage is developed at member 29.

It will be observed that the sequence of the four voltages developed is that of positive, negative, positive, negative, so that if these voltages are connected in an electrically series relationship, the total voltage will be the sum of the voltages produced.

Referring to Fig. 3, the tilting of the central section of electrode members is illustrated. It will be noted that the proper positive, negative sequence is observed throughout the successive electrodes, the connections of wires 39 and 40 carrying out this purpose. The voltage between terminal 37 and 38 will be substantially the sum of all the separate voltages developed between each electrode member. In the arrangement shown, the row of central electrode members transverse to the pivoted section have their copper sides uppermost in order to preserve such sequence, as will be apparent by following the voltages developed throughout the series circuit.

The lateral spacing between adjacent plates is arranged to be considerably smaller than the spacing between plates which do not follow in the series relationship. For example, the spacing between electrode members 25 and 26 may be in the order of .002 inch, while the spacing between the same member 25 and member 26 may be .125 inch. Considering a typical ethylene glycol predominant electrolyte, the electrical resistance between members 25 and 26 may be approximately 7500 ohms, while the resistance between members 25 and 29 may be approximately 75,000 ohms. This arrangement will favor the series relationship hereinabove described in that

the electrolytic solution functions as an electrical connection between the cells described. If desired, an electrolyte having a gelatin base may be employed. In this event, the gelatin itself may contribute to the support of the electrode members.

The higher resistance of the electrolyte between adjacent electrode members not of the same group of three, impedes electrolytic co-action in other than the series relationship. The term "group of three" refers to three electrode members arranged for co-action as illustrated in Fig. 2, and wherein the turnable element produces additive voltages.

The relatively high resistance electrolyte produces a very slight de-activating effect upon the electrode members, the effect being so slight as to be entirely unnoticeable even after a considerable period of time. The instant device permits the use of such an electrolyte because practically no current is drawn therefrom, the pick-up merely serving to produce voltages for application to the grid of a vacuum tube. Since a vacuum tube is a voltage actuated device, a further advantage of such construction is that the pick-up or voltage generating device has an extremely long life because no current is drawn therefrom. In this respect, its life is much greater than the so-called "shelf-life" of a battery because even after the usefulness of a conventional battery is outlived it still produces voltages if very minute currents are drawn therefrom.

Opposite voltages will be developed as the externally actuated needle vibrates at sound frequencies and re-orient the plane of the movable section comprising the center member of each group of three electrode members so that the proper audio frequency voltages are supplied between the terminals 37 and 38.

In the event the device of Fig. 1 is applied to a simple vacuum tube apparatus, terminal 37 may be connected to the ground side thereof, while terminal 38 may be applied to the grid of the input tube. The impedance of the unit may be regulated by the character of the electrolyte and the spacing between the electrode members so that high and low impedances are easily realized. In the event that a push-pull input is being served, the central electrode 18 may be grounded, whereupon opposite or out-of-phase voltages will be developed at terminals 37 and 38. Thus, the requirements for push-pull operation will be met.

As illustrated in Fig. 2, the co-acting sides of the respective electrode members are brought to a sharp edge in order to produce greater sensitivity to slight actuation of the pivoted section while the corrugations 13 in the thin floor 12 permit pivoting of the section in response to such actuation.

While Fig. 1 shows a successive group of cells contributing to the total voltage through series operation, it will be understood that a single pair of cells, one of which is movable in the manner described, while the other remains stationary, is operative for the purposes of this invention. A simple combination, such as three electrode members disposed in Fig. 2 but wherein the terminals emerge from electrode members 26 and 29, is likewise feasible, the combination representing two cells which are series operated to produce additive voltages.

In the embodiment of Fig. 4, a section similar to that of Fig. 2 is shown, but with a modified disposition of the electrode plates. The center electrode 45 has its zinc plate uppermost and,

as will be noted in Fig. 5, the end electrodes of the turnable section have their copper plates uppermost. The laterally disposed stationary sections comprise separated plates such as the copper plate 46 and the zinc plate 47 which are maintained in their spaced relationship by a conducting metal 48 and are suspended in an electrolyte which fills the hollow body 51. An electrically conducting rod 52 embedded in the wall of the device serves as one terminal and in the arrangement shown in Fig. 4 it will be connected to the member 48 which connects the zinc plate 46 to its associated copper plate. Similarly, a member 54 connects the oppositely disposed copper plate 55 and zinc plate 56, while the electrical lead rod 57 serves as the other terminal of the device, being connected to the member 54. In Fig. 5, which illustrates the modification of Fig. 4 as adapted to a plurality of groups of three electrode members, the terminals 49 and 50, corresponding to terminals 52 and 57, are connected to the respective ends of the circuit.

When the electrode member 45 is pivotally actuated by the movement of the phonograph needle 59, as indicated in the dotted lines of Fig. 4, the balanced relationship existing between the electrode plates will be disturbed and the copper plate of member 45 will present a considerable area for co-action with the zinc plate 47, while the zinc side of member 45 will be correspondingly withdrawn from copper plate 46. Accordingly, a negative voltage will be developed at zinc plate 56 which overcomes the neutralizing positive voltage which is ordinarily created by the copper plate 46. Thus, the metal connecting member 52 will have a negative potential. On the opposite side of the unit, opposite conditions will prevail, a positive potential being developed at connecting member 54.

As noted in Fig. 5, conducting wires 60 and 61 maintain the series relationship of the various cell structures. It will be appreciated, of course, that the stationary electrode members are constructed as are the illustrated cell members 46 and 47, and 55 and 56, while the pivoted section has the cell members or plates in contacting relationship.

In the event of a simple input to an amplifier, terminal 49 or 52 may be connected to the ground thereof, while terminal 50 or 57 may be introduced in any suitable manner to the grid of a vacuum tube. If push-pull operation is desired, an insulated wire may be connected to the electrode member 45. This electrode member 45 being the electrical center of the unit, may be connected to the ground side of the amplifier, whereupon wires 52 and 57 or 49 and 50, will produce mutual out-of-phase voltages for application to a pair of grids in the push-pull input. As in the previous embodiment, either the series of nine or more electrode members may be utilized, or a simple combination of either two or three. A combination of three would appear as illustrated in Fig. 4.

It will be appreciated that the liquid electrolyte produces an inherent damping effect and contributes to the tonal fidelity of the system. The pick-up is, furthermore, light in weight and produces high voltages by the series action described. If desired, a de-polarizing agent of a conventional type may be utilized to eliminate the effects of polarization of electrode surfaces. Such polarization will be extremely small, however, because practically no current is supplied by the device in normal operation.

I have shown a preferred embodiment of my invention, but it is obvious that numerous changes and omissions may be made therefrom without departing from its spirit. The corrugations 13 may be omitted if the floor is sufficiently flexible and in this event, it may be desirable to omit the pivot members 23 and 24 since the electrode members may have a lateral as well as a pivotal movement.

I claim:

1. A voltage generating device of the character described comprising a chamber, a pair of electrode members fabricated of dissimilar metallic materials which form positive and negative electrodes respectively when immersed in an electrolyte, said electrode members being mounted in said chamber, an electrolyte within said chamber and in which said members are disposed so that voltages tend to develop across said electrode members through electrolytic coaction, and vibrating means disposed externally of said chamber and connected to one of said electrode members so as to vibrate said connected member and vary its electrolytic coaction with the other electrode member.

2. A voltage generating device of the character described comprising a chamber, a pair of electrode members fabricated of dissimilar metallic materials which form positive and negative electrodes respectively when immersed in an electrolyte, said electrode members being mounted in said chamber, an electrolyte within said chamber and in which said members are disposed so that voltages tend to develop across said electrode members through electrolytic coaction, means to normally maintain said electrode members in a plane wherein no voltages are developed between them, and movable means originating externally of said chamber for varying the plane of one of said members, said variation being operative to affect the electrolytic coaction of said members so as to develop alternating voltages accordingly.

3. A voltage generating device of the character described comprising a chamber, at least three electrode members mounted within said chamber, an electrolyte within said chamber in which said members are disposed, means to develop opposite voltages between the center electrode member and the electrode members on each side thereof through electrolytic action of said members, said center member being movable in response to external actuation, means to move said center member, said movement being operative to develop alternating voltages of opposite polarity in the respective electrode members on each side of said center electrode member through electrolytic action.

4. A voltage generating device according to claim 3 wherein said three members are normally oriented in a balanced relationship wherein no voltages are generated between them, and means originating externally of said chamber for re-orienting said central member, said re-orientation being operative to effect opposite coaction of said center member with the other two members respectively so as to produce opposite voltages thereon.

5. A voltage generating device of the character described comprising a chamber, three electrode members mounted within said chamber, an electrolyte within said chamber in which said three members are disposed, each said member comprising a pair of opposite electrode plates, the

opposite plates of the center member of said three members being arranged for respective coaction with one electrode plate of the electrode members on each side thereof, said co-action producing opposite voltages on each of said end electrode members in respect to said center electrode member, and means adapted to vary the position of said center electrode member at an audio frequency rate whereby said co-action produces opposite alternating voltages between said electrode member and said end members respectively.

6. A voltage generating device of the character described comprising a chamber, three electrode members mounted within said chamber, an electrolyte within said chamber in which three members are disposed, each said member comprising a pair of opposite electrode plates, the opposite plates of the center member of said three members being arranged for respective co-action with one electrode plate of the electrode members on each side thereof, said co-action producing opposite voltages on each of said end electrode members in respect to said center electrode member, all of said three members being normally in alignment so as to balance the co-action of said center member with the other members whereby no voltages are produced through electrolytic action, and means disposed externally of said chamber and operatively connected to said center electrode so as to disturb said alignment whereby the co-acting surfaces of the opposing electrode members are varied, said variations being operative to produce opposite reactions on both sides of said center electrode member.

7. A voltage generating device of the character described comprising a chamber, three electrode members mounted within said chamber, an electrolyte within said chamber in which said three members are disposed, each said member comprising a pair of opposite electrode plates, the opposite plates of the center member of said three members being arranged for respective co-action with one electrode plate of the electrode members on each side thereof, said co-action producing opposite voltages on each of said end electrode members in respect to said center electrode member, and means adapted to vary the position of said center electrode member at an audio frequency rate whereby said co-action produces opposite alternating voltages between said electrode member and said end members respectively, said end electrode members having their electrode plates disposed similarly, and said center electrode member having its electrode plates disposed oppositely with respect to said end member plate disposition.

8. A voltage generating device of the character described comprising a chamber, at least three electrode members mounted within said chamber, an electrolyte within said chamber in which said members are disposed, means to develop opposite voltages between the center electrode member and the electrode members on each side thereof through electrolytic action of said members, said center member being movable in response to external actuation, means to move said center member, said movement being operative to develop alternating voltages of opposite polarity in the respective electrode members on each side thereof, said electrolyte being of high resistance and being operative to connect said voltages in a series relationship.

9. A voltage generating device for feeding audio

frequency voltages to a voltage operated amplifier thereof, comprising a chamber, a pair of dissimilar electrode members mounted therein, an electrolyte of high resistance within said chamber in which said members are disposed so that voltages tend to develop across the electrode members through electrolytic action, a vibrating device external of said chamber and connected to one of said electrode members, and means to pivot said connected electrode member through the action of said vibrating device so as to vary said electrolytic co-action and produce alternating voltages therefrom, said electrode members being connected to said voltage operated amplifier so as to feed the same with said alternating voltages.

10. A voltage generating device of the character described comprising a chamber, a plurality of electrode members arranged in an electrical series relationship in said chamber, an electrolyte within said chamber in which said members are disposed so that voltages tend to develop across adjacent electrode members through electrolytic action, said electrode members being arranged in groups of three, means to electrically connect each group so as to effect the series relationship, one member of each group being movable so as to produce varying voltages through electrolytic co-action with the other members of said group, and means to produce said movement in response to external excitation whereby variable voltages are produced pursuant to said excitation.

11. A voltage generating device according to claim 10 wherein the center member of each group of three is movable, the movement of said center member affecting opposite co-actions respectively with each end member of its group, said co-action producing opposite voltages at each of said end members, the voltages produced by said end members being combined with the voltages produced by the remaining groups in a series relationship.

12. A voltage generating device according to claim 10 wherein each electrode member comprises a pair of dissimilar metallic members, adapted for electrolytic co-action with the metallic members of an adjacent electrode member in its group.

13. A voltage generating device of the character described comprising a chamber, a plurality of electrode members arranged in an electrical series relationship and in groups of three within said chamber, a fluid electrolyte within said chamber, each said electrode member being formed of two opposed dissimilar metallic materials, each electrode member of each group of three thereof being normally in alignment whereby no voltages are produced in end electrode members of each group of three through balanced co-action of said electrode members, the center electrode member of each group being movable to disturb said normal alignment, said disturbance being operative to produce opposite voltages upon the end members of said group through electrolytic action, and means responsive to external excitation to disturb said normal alignment so as to develop said opposite voltages upon the end members of each said group, all the voltages developed in each group being electrically added to form an aggregate voltage at the electrical terminals of the device.

14. A voltage generating device according to claim 13 wherein said means responsive to external excitation comprises a pivoted member operatively connected to the center electrode members of each group, and a phonograph needle secured to said pivoted member so as to pivot the same

pursuant to sound grooves in a phonograph record.

15. A voltage generating device according to claim 13 wherein said electrolyte is of high resistance and adjacent electrode members of each group are spaced less apart than adjacent electrode members of different groups.

16. A voltage generating device of the character described comprising a chamber, an electrolyte within said chamber, a plurality of electrode members arranged in an electrical series relationship in said electrolyte, said electrode members being arranged in groups of three, said electrode members each comprising dissimilar metallic plates adapted to effect electrolytic co-action with the plates of an adjacent electrode member, the end electrode member of each group of three having its dissimilar plates spaced in said electrolyte, electrical connecting means for said spaced plates, the center electrode member of each group being movable between said end electrode members, said movement serving to produce varying voltages upon said end members by varying the areas of co-action therewith, and means pursuant to external excitation for effecting the movement of said center electrode members.

17. A voltage generating device of the character described comprising a chamber, an electrolyte within said chamber, a plurality of electrode members arranged in an electrical series relationship in said electrolyte, said electrode members being arranged in groups of three, an electrical conducting wire between the end of one group and the beginning of the next group, said electrolyte serving as an electrical conductor between adjacent electrode members of the same group, each of said electrode members comprising dissimilar metallic plates adapted to effect electrolytic co-action with the plates of an adjacent electrode member through the action of said electrolyte, the center electrodes of each group of three being connected together so as to be movable in common, said connected center electrode members being swingable so as to vary the action of said center electrode members with the end electrode members of each group of three, said center electrode members being normally disposed in a plane which is symmetrical to the plane of said end electrode members so as to produce equal and opposite electrical voltages with each end electrode member, and means originating externally of said chamber for varying the plane of said movable electrode members whereby opposite but unequal voltages are produced in the center electrode members with the respective end electrode members of each group of three so as to produce resultant voltages between each end electrode member and a central electrode member, said series relationship of said groups of three being operative to add said resultant voltages to produce a total voltage between the first and last electrode members of said device.

18. A voltage generating device of the character described comprising a chamber, a pair of electrode members fabricated of dissimilar metallic materials which form positive and negative electrodes respectively when immersed in an electrolyte, said electrode members being mounted in said chamber, an electrolyte within said chamber and in which said members are disposed so that voltages tend to develop across said electrode members through electrolytic co-action,

and means originating externally of said chamber and connected to one of said members for moving said one member so as to vary the extent of co-action of said members and thereby vary the developed voltages accordingly.
